JOEL G. GARRETSON AND FRANKLIN D. CLARK, OF BUFFALO, NEW YORK.

Letters Patent No. 71,603, dated December 3, 1867; antedated November 19, 1867.

IMPROVED SASH-STOP.

The Schedule referred to in these Letters Patent and making part of the same.

TO ALL WHOM IT MAY CONCERN:

Be it known that we, JOEL G. GARRETSON and FRANKLIN D. CLARK, of the city of Buffalo, in the county of Erie, and State of New York, have invented certain new and useful Improvements in Sash-Locks; and we do hereby declare that the following is a full and exact description thereof, reference being had to the accompanying drawings, making part of this specification, in which—

Figure 1 is a section through a portion of a window-casing, with a portion of the plate of the lock broken away, showing a front elevation of the lock and a portion of the sash.

Figure 2, an edge view of the lock secured in place in the casing.

Our invention consists in the combination of two cams or eccentric segments geared together by teeth meshing into each other, so that when partially rotated on their axes in one direction their faces are forced simultaneously against the sash, holding it both from falling and being raised; and when turned in the opposite direction, recede therefrom in like manner, being self-operating in lock, by means of a weighted portion, together with the additional weight of the thumb-lever, and unlock by pressing against said lever; and it further consists in the manner of constructing the case for holding said cams and lever, with a combination of slots or recesses therein, by means of which one side of said case is made to form, by the casting of a single plate, both a way or passage in which said thumb-lever moves, and a guard to retain it in position, instead of the latter being composed of a separate piece, riveted or otherwise attached, as ordinarily required.

In the drawings, A represents a portion of the side rail of a sash, and B a contiguous portion of the window-casing. C, the case of the lock, with two side plates, between which the two toothed cams or segments D E are pivoted, by means of pins *a a*, cast with and projecting from the back plate *b* of the case. The cams mesh together by means of teeth *c c*, and are provided with faces *d d*, of the form shown, both of which engage with the edge of the sash, as shown in black lines, fig. 1, wedging against it in such a manner as to prevent it being moved in either direction. This cam E is weighted or made heavier at *e*, the gravity of which, combined with the thumb-lever, presently to be described, causes them to act automatically, by keeping their faces in contact with the edge of the sash, the friction between the contiguous surfaces being sufficient to produce the necessary wedging. The sash is released by means of a thumb-lever, F, that is pivoted to the cam E, by means of a projecting pin cast therewith, as shown in fig. 1, which being pressed in partially rotates the cams, removing their faces from contact with the sash, as clearly represented in the red lines, fig. 1. The weight of this lever also assists the portion *e* in rendering the lock automatic in its action, as above specified. The side, H, of the case, or that on which the arm F is pivoted, is cast with the edge *i* of the case, and is formed with a portion, *f*, in relief or elevated, with recesses or slots, *m s*, on each side, to allow the passage of the arm beneath, as represented, forming a way for the same to slide in, while the tongue *f* operates as a guard to retain it in place. This elevated portion may be extended to *f'*, where it further operates as a cap or guard to keep the end of the lever engaged with its pivot-pin.

The lock is inserted in a mortise formed in the window-casing, and then fastened by screws *o*, through the flanges *p p*, as shown in fig. 2. It is cast in five pieces, ready to put together without drilling or filing. A single rivet, *r*, may be employed to retain the case together. When secured in the window-casing, it is hid from view except the end of the thumb-lever, and consequently does not present that ungainly and objectionable appearance which many other kinds do that are attached on the outside to the casing or sash. It is easily operated, securely holds the sash in whatever position required, locking it down, as well as holding it up.

The construction of the plate H of the case, so as to form a way for the arm F, while the tongue *f* secures it in place, dispenses with the use of a separate guard-piece, as is ordinarily required, as well as the expense of riveting or otherwise attaching it to the case.

What we claim as our invention, and desire to secure by Letters Patent, is—

The eccentric segments D E, geared together, and self-operating, by means of the weighted portion *e*, and lever F, arranged and operating substantially as and for the purposes set forth.

In witness whereof, we have hereunto signed our names in the presence of two subscribing witnesses.

JOEL G. GARRETSON,
FRANKLIN D. CLARK.
